UNITED STATES PATENT OFFICE.

ERNEST H. GOSEWISCH, OF CHICAGO, ILLINOIS.

RUCHING.

SPECIFICATION forming part of Letters Patent No. 449,116, dated March 31, 1891.

Application filed April 16, 1890. Serial No. 348,254. (No model.)

To all whom it may concern:

Be it known that I, ERNEST H. GOSEWISCH, a citizen of the United States, residing at Chicago, in the county of Cook and State of Illinois, have invented certain new and useful Improvements in Ruchings, of which the following is a specification.

The present invention relates to ruching adapted to be used for trimming millinery, dresses, and other articles of apparel, and for making and trimming fancy articles of various kinds.

The invention consists of certain features of novelty, which are particularly pointed out in the claims hereinafter.

Of the accompanying drawings, which form a part of this specification, Figure 1 is a perspective view of a short piece of the improved ruching. Fig. 2 is an end view thereof on a larger scale. Fig. 3 is an elevation showing one way in which the initial loops may be made. Fig. 4 is a diagram showing the relations of the several initial loops to each other. Fig. 5 is a section thereof on the line 5 5. Fig. 6 is a diagram showing the relations of the several initial loops to each other after they are folded or doubled upon themselves. Fig. 7 is a section thereof on the line 7 7. In Figs. 1, 2, 3, 5, and 7 the thickness of the ribbon is exaggerated for the sake of clearness.

To make the improved ruching, a strip of ribbon or similar material is folded continuously or wound in a spiral fashion into a number of flat initial loops *a b c*, &c., which are shown in diagram in Fig. 4. In practice the whole ruching is formed by a machine; but the present application relates to the article itself and is not, therefore, concerned with the mechanical contrivance for producing it. These initial loops may be formed by winding the strip of ribbon in a spiral fashion around two pins *p*, situated at the required distance apart, as suggested by Fig. 3. They are then transversely folded or doubled upon themselves on a line between their extremities for the purpose of forming of each of them two separate loops, as shown at *A A' B B'*, &c. This provides two rows of loops extending side by side, the axes of all the loops of each row being coincident, so that

in the completed ruching all of the loops will lie in planes transverse to its longitudinal axis. Fig. 6 is a diagram of these initial loops after they have been folded or doubled on the line 6 6, Fig. 5. This line 6 6 is not at the middle of the initial loops, and consequently the resulting loops *A B C*, &c., on one side of the fold are not the same size as the loops *A' B' C'*, &c., on the other side of 60 the fold. The loops thus formed are secured together by stitching passing through the several folds, as indicated at *s*. It will be understood that if the initial loops are folded at their middle, the resulting loops upon opposite sides of the fold will be equal in size.

This ruching is designed to be used for all purposes for which similar material is or can be used. It may be used in strips for trimming articles of apparel or fancy articles, for 70 making fancy articles, and for many other purposes.

It will be seen that the several loops are not all stitched to a separate binding-strip, as is customary in trimmings of this sort. I am 75 enabled to dispense with these separate binding-strips by so arranging the loops that they break joints on the line upon which they are to be stitched. Thus, referring to Fig. 5, the under side of loop *a* overlaps the adjacent edges of its own upper side and the upper side of the next loop *b*. Similarly the upper side of this loop *b* overlaps the adjacent edges of its own under side and the under side of the loop *a*, and the under side of 85 this loop *b* overlaps the adjacent edges of its own upper side and the upper side of the next loop *c*, and so on.

The drawings show the ribbon wound with a small space between its adjacent edges, 90 which of course causes similar spaces between the adjacent edges of corresponding parts of the several loops. This space may be increased so long as it is not made as wide as the ribbon itself, for if it were there would 95 be no single line on which the opposite sides or folds of all the loops would break joints, as above described; or, if desired, the ribbon may be wound or folded in such a manner that its adjacent edges will touch or even 100 overlap slightly, thereby leaving no space between the loops.

Having thus described my invention, what I claim as new therein, and desire to secure by Letters Patent, is—

1. The herein-described ruching, consisting of loops of ribbon whose planes are transverse to the longitudinal axis of the ruching, and stitching by which said loops are secured together, the stitched portions of the loops being arranged to overlap.
2. The herein-described ruching, consisting of loops of ribbon whose planes are transverse to the longitudinal axis of the ruching, arranged in a plurality of rows extending side by side, and stitching by which said loops are secured together, the stitched portions of said loops being arranged to overlap.
3. The herein-described ruching, consisting of loops of ribbon whose planes are transverse to the longitudinal axis of the ruching, and stitching by which said loops are secured together, the opposite sides or folds of the loops being arranged to break joints at their stitched portions.
4. The herein-described ruching, consisting of loops of ribbon whose planes are transverse to the longitudinal axis of the ruching, arranged in a plurality of rows extending side by side, and stitching by which said loops are secured together, the loops of one row being arranged to break joints with the loops of the next row at their stitched portions.
5. The herein-described ruching, consisting

of loops of ribbon whose planes are transverse to the longitudinal axis of the ruching, the ribbon being in one continuous strip, and stitching by which said loops are secured together, the loops being arranged to overlap at their stitched portions.

6. As a new article of manufacture, the ruching, substantially as herein described, consisting of a strip of ribbon coiled, providing a number of loops having coincident axes, and stitching by which said loops are secured together, the opposite sides or folds of the said loops breaking joints on the line of the stitching.

7. As a new article of manufacture, the ruching, substantially as herein described, consisting of a coiled strip of material folded transversely, providing two rows of loops extending side by side, and stitching by which the rows of loops are sewed together.

8. As a new article of manufacture, the ruching, substantially as herein described, consisting of a coiled strip of material folded transversely, providing two rows of loops extending side by side, one row of loops breaking joint with the other row of loops, and stitching by which the rows of loops are sewed together.

ERNEST H. GOSEWISCH.
